CLAIM

The ornamental design for a silverware organizer, as shown and described.

DESCRIPTION

FIG. 1 is a perspective bottom view of the invention;
FIG. 2 is a perspective top view thereof;
FIG. 3 is a straight top view thereof;
FIG. 4 is a straight top view with environment included thereof; and,
FIG. 5 is a front perspective view thereof.
There are dotted and dashed lines that indicate environment and the dash dot dash line designates a design border, none of which comprise any of the claimed design.

1 Claim, 5 Drawing Sheets
